US00D815106S

(12) **United States Design Patent** (10) Patent No.: **US D815,106 S**
(45) Date of Patent: ** Apr. 10, 2018

(54) **ELECTRONIC FOB**

(71) Applicant: **BLOOMBERG FINANCE L.P.**, New York, NY (US)

(72) Inventors: **Helmar E. Ozolins**, Orient, NY (US); **Avram Kaufman**, New York, NY (US); **Adam Goldsmith**, Larchmont, NY (US); **Sean Roarty**, Ossining, NY (US); **Sigrid G. Moeslinger**, New York, NY (US); **Masamichi Udagawa**, New York, NY (US)

(73) Assignee: **BLOOMBERG FINANCE L.P.**, New York, NY (US)

(**) Term: **15 Years**

(21) Appl. No.: **29/550,568**

(22) Filed: **Jan. 5, 2016**
